UNITED STATES PATENT OFFICE.

HYMAN BLUMBERG AND LEON JACOBSON, OF NEW YORK, N. Y.

BOTTLE-FILLING APPARATUS.

SPECIFICATION forming part of Letters Patent No. 571,104, dated November 10, 1896.

Application filed January 2, 1896. Serial No. 574,034. (No model.)

To all whom it may concern:

Be it known that we, HYMAN BLUMBERG and LEON JACOBSON, citizens of the United States, and residents of New York city, county 5 of New York, and State of New York, have invented certain new and useful Improvements in Bottle-Filling Apparatus, of which the following is a specification, reference being had to the accompanying drawings, forming a part thereof, in which similar letters of reference indicate corresponding parts.

This invention relates to improvements in bottle-filling apparatus, and has for its object to provide a handy and portable device 15 of this character adapted for drawing off liquid from casks, kegs, or other closed vessels. The device comprises few and simple parts, can be readily operated, and is inexpensive and durable.

20 The invention will be hereinafter fully described, and specifically set forth in the annexed claim.

In the accompanying drawings, Figure 1 is a perspective view showing our improved apparatus attached to a barrel, and Fig. 2 is a sectional elevation taken on a line xx of Fig. 1.

In the practice of our invention we provide a distributor, comprising a flattened and closed compartment A and a tubular inlet a. 30 Leading downwardly through the compartment A from a tightly-fitting partition a are a series of tubes B. These said tubes are composed of block-tin and terminate at the lower wall a² of the compartment A. Depending downwardly from this said wall a² and communicating with the lower ends of the tubes B are other tubes B'. These said tubes are composed of brass or other suitable metal which will not readily bend; but in order to protect the liquid adapted to pass 35 through them they must be supplied with an interior coating b of tin, whereby the combination of the tubes B with the tubes B' will produce continuous tubular channels of tin, which metal will not have any deleterious effect upon beer or other liquid adapted to pass through the apparatus.

In order to insure that an equal amount of liquid will be contained within each of the 40 tubes B, they must all be of exactly the same length. They are therefore bent into compound curves, as illustrated in Fig. 1.

The inlet-channel a is provided with a valve C, adapted to control the flow of liquid therethrough.

To complete the operative parts of the device a flexible tubular channel D is provided. This channel is connected at one end with the inlet a, and it is provided with a sliding cork or bung d, which cork is adapted to engage 55 with a bunghole of a barrel, cask, or other vessel being emptied.

To the lower or outer end of the flexible tube D we attach a screen d'. This will prevent anything but liquid substance from entering the 60 tube D. At a point near the juncture of the tube D with the inlet a we provide the said tube with an arm or branch D', to the outer end of which branch is attached a hollow screw-plug d², which plug engages with a 65 screw-cap d³.

In the operation of the device the bung of a barrel or cask is removed in the ordinary way. The end of the tube D which carries the hollow bung d is then projected downwardly into the barrel, and the bung d is brought into tight engagement with the bunghole e of the barrel E. The tubes B' are then inserted, respectively, into the necks of the bottles. The cap d² is then removed from the 70 plug d³ and suction is applied from the plug d³ through the branch D' and the tube D until the liquid starts to flow from the barrel, after which the cap d² can be replaced and the valve C opened, thus permitting the 75 liquid to siphon out of the barrel until the bottles are filled, when the valve C must be closed and another set of bottles brought into engagement with the tubes B'. This operation can be repeated until the barrel is 80 emptied, when the apparatus can be readily removed therefrom and attached to another barrel, cask, or other vessel which it is desired to empty.

We do not confine ourselves to the specific 85 detail of mechanical construction as illustrated in the drawings and herein described, as it is obvious that under the scope of our invention we are entitled to make slight changes.

Having thus described our invention, what we claim as new, and desire to secure by Letters Patent, is—

In a bottle-filling apparatus, the combina-

tion of a flexible siphon having a capped branch and a tubular valved outlet leading therefrom, which outlet engages with a partition in the contracted upper portion of a closed triangular compartment, said partition having leading therefrom a plurality of block-tin tubes which are all of the same length and which are spread apart at their lower ends and extended through the lower wall of the said triangular compartment and respectively joined to depending tubes of equal

length adapted to discharge liquid into bottles, substantially as shown and described.

In testimony that we claim the foregoing as our invention we have signed our names, in presence of two witnesses, this 31st day of December, 1895.

HYMAN BLUMBERG.
LEON JACOBSON.
